UNITED STATES PATENT OFFICE.

GEORGE F. OLSEN, OF LOS ANGELES, CALIFORNIA, ASSIGNOR TO GENERAL PETROLEUM CORPORATION OF CALIFORNIA, A CORPORATION OF DELAWARE.

NEUTRALIZING TREATMENT OF ACID OILS FOR LUBRICANT STOCKS.

No Drawing.

Application filed August 31, 1926. Serial No. 132,801.

As may be inferred from the above title, this invention relates particularly to the neutralization or partial neutralization of oils such as are obtainable by a gravity separation from an acid sludge; but it should be understood that the principles of my present invention are not limited to the treatment of acid oils designed for use in the production of lubricants.

10 Although it is an object of my invention to provide a neutralizing treatment which is especially suitable for use upon acid oils containing waxes, such as the acid oils produced by a process set forth in my application (Case "A") Serial No. 140,823, filed October 11, 1926, entitled Method of acidifying oils for lubricant stocks, features of my present invention are applicable also to oils which do not contain waxes, and regardless 20 of the extent to which the previous acidification may be carried.

It is a primary object of my invention, in which I may advantageously employ a finely divided non-aqueous alkaline neutralizing 25 reagent (introduced subsequently to an addition of any subdivided and dry solid which may be used for a purely physical effect—both of the mentioned additions being preferably made to an acid oil whose viscosity is 30 not higher than about 100 Saybolt universal) to add to the acid oil only sufficient alkali to neutralize any so-called "mineral" acidity remaining therein,—without appreciably attacking such naphthenic, or other organic, 35 acids as may be present.

In the practice of this invention, in which I may use either a gaseous or a liquid or a "creamy" reagent (examples being, ammonia, NaOH, KOH, "dry" or in solution, 40 and milk of lime) my preferred neutralizing agent may be ordinary "soda ash," triturated into a small quantity of an oil identical with or similar to that to be treated.

As will be seen from the foregoing, there 45 need be no novelty either in the acid oil stock used, or in the neutralizing agent employed in my process,—the outstanding feature thereof being such a limitation of the neutralizing step as to avoid the formation 50 of naphthenic and/or sulphonate salts or soaps.

It is an object of my invention to avoid the formation of soaps,—requiring subsequent decomposition, followed by decolorizing 55 steps.

It is an object of my invention to obviate the need for use of large quantities of clay, subsequently to a neutralization of acid oil, and to obviate or substantially reduce the loss of oil in such clay.

Although I herein emphasize the advantages of my novel process of neutralization in the production of an oil stock which, when finished, is exceptionally free from contained or dissolved soaps, calling attention also to economy in the use of a neutralizing agent such as soda ash, or the like, introduced in an attenuated state (but preferably without an addition of water) and to an incidental avoidance of waste in clay and in oil, it is 60 an important merit of my present invention (which may be regarded as especially suitable for use subsequently to a complete or partial acidification executed in the special manner set forth in my mentioned application Serial No. 140,823) that the process of 65 the present invention tends to keep in the oil certain valued ingredients, for treatment in accordance with steps set forth in my other copending applications, (including Case "C", Serial No. 141,040, filed October 11, 1926)—one feature of the process set forth in the last mentioned case being a 70 novel and advantageous use of a light hydrocarbon or mixture such as an ordinary gasoline (preferably of high initial boiling point and of low end point) in an amount sufficient to bring the gravity of the resultant 75 solution to about 37-44° A. P. I., the viscosity of the resultant mixture (comparable 80 with that of kerosene) thereby becoming so 85 low that undesired solids are readily precipitable therefrom.

As a specific example of my invention, I 90 may slightly thin in a so-called sweetening agitator, or the like, any appropriate batch (as, a batch from any tank or agitator, in which sludge has been separated therefrom,—such a batch presumably amounting to 250 to 2000 barrels of acid oil) by adding 95 thereto, if the viscosity of the acid oil is above 100 Saybolt universal, sufficient gasoline to bring the same approximately to this standard consistency at the temperature of operation,—which may be, say 70°-150° F.; 100 and/or I may add, without resort to any test or calculation, sufficient of a dried pulverulent solid (as, a suitable clay) to agglomerate and adsorb floating "specks" of acid—the intended effect of this preliminary 110

addition being purely physical, although such as practically to prevent the acid adsorbed in the clay from entering into a subsequent neutralizing reaction; and I may 5 then add to the acid oil mixture, before or during blowing of the same (and without directing any separate effort to the removal of the clay, or its equivalent, with its adsorbed acid) suitable quantities of soda ash, 10 or the like,—preferably initially triturating the soda ash in a small quantity of the same or a similar oil and continuing the agitation while repeatedly testing withdrawn portions of the agitated mixture by means 15 of a reagent such as methyl orange.

An alcoholic solution of the test reagent may be employed in a known manner, and small additions of the neutralizing agent may be continued until tests upon the withdrawn 20 samples show the known color change in the test reagent from orange to yellow, indicating the completion of only the intended neutralization of mineral acid. In case of a 2000 barrel batch, somewhere between 25 50 pounds and 250 pounds of soda ash may be required for the purpose referred to, and care should be taken not substantially to exceed the degree or point of partial neutralization referred to.

Whether or not agitation is continued for a brief period subsequent to the discontinuance of neutralization, this neutralization being such as to leave the naphthenic and sulfo acids substantially unattacked, any 30 subsequent addition of decolorizing clay may be reduced to (say) one-fourth or one-half of that which has been customarily employed subsequently to a complete neutralization of acid oil (up to a point testable by 35 phenol phthaleine,—an addition of alkali up to the point last referred to, being effective to produce the undesired naphthenic and sulphonic soaps; and this minimization of clay obviously implies an approximately 40 corresponding diminution in the loss of oil therewith in a sludge.

Although, as suggested in my first mentioned companion application (Case "A") I may prefer, in the treatment of a material such as a "Bunker B" fuel oil for the production of lubricant stocks, to acidify in such manner as substantially to avoid attack upon these contained naphthenes (these being, in the case assumed, intended to remain 50 in a lubricant ultimately obtained) and although I may advantageously treat a partially neutralized product obtained in the general manner above described in subsequent processes involving the addition thereto of a considerable quantity of gasoline, (as in, for example, my Case "C") I emphasize

herein the fact that my described method of neutralization, economical in its use of neutralizing agents (and advantageous also in its simplification of subsequent steps, in its conservation of values and in its avoidance of the production of soaps and the loss of oil in decolorizing clays) is very generally applicable in the treatment of acid oils,—whether or not diluted and/or clay-treated. 70

Although I have herein described a single complete embodiment of my invention, it should be understood not only that various features thereof may be independently used but also that numerous modifications 75 might be made by those skilled in the art to which this case relates, without the slightest departure from the spirit and scope of this invention, as the same is indicated above and in the following claims; and in connection with my present description and claims it should be clearly understood that I herein use the term "acidity" to include not only a hydrogen concentration due to such true mineral and/or organic acids as may be 80 present in the oil, but to include also allied bodies naturally occurring in the oil or formed therein and therefrom during the refining process.

I claim as my invention:

1. In the treatment of acid oils containing organic acidity as well as mineral acidity, a method of neutralization characterized by the fact that a comminuted solid alkali is added in quantity sufficient to neutralize 95 the mineral acidity only, said neutralizing agent being added in successive small quantities during agitation, the presence of water being avoided throughout.

2. In the treatment of acid oils containing 100 organic acidity as well as mineral acidity, a method of neutralization characterized by the fact that an alkali is added in quantity sufficient to neutralize the mineral acidity only, the neutralizing agent being soda ash 105 previously triturated in a small quantity of oil, and the presence of water being avoided throughout.

3. In the treatment of acid oils containing 110 organic acidity as well as mineral acidity, a method of neutralization characterized by the fact that a comminuted solid alkali is added in quantity sufficient to neutralize such portion of the total acidity as is indicated by a change from an acid to a neutral 115 reaction when the oil is tested with an alcoholic solution of methyl orange.

In testimony whereof, I have hereunto set my hand at Los Angeles, California, this 5th day of August, 1926.

GEORGE F. OLSEN.
